US0D1109109S

(12) **United States Design Patent** (10) Patent No.: **US D1,109,109 S**
(45) Date of Patent: ** Jan. 13, 2026

(54) **CONTROL PANEL**

(71) Applicant: **EMOMO TECH (ZHEJIANG) CO., LTD**, Zhejiang (CN)

(72) Inventors: **Wenji Tang**, Zhejiang (CN); **Dasheng Hu**, Zhejiang (CN); **Jun He**, Zhejiang (CN); **Zaigui Yang**, Zhejiang (CN); **Guifeng Zhou**, Zhejiang (CN)

(73) Assignee: **EMOMO TECH (ZHEJIANG) CO., LTD**, Huzhou (CN)

(**) Term: **15 Years**

(21) Appl. No.: **29/980,400**

(22) Filed: **Dec. 24, 2024**

(30) **Foreign Application Priority Data**

Jul. 31, 2024 (CN) 202430480604.5

CLAIM

The ornamental design for a control panel as shown and described.

DESCRIPTION

FIG. 1 is a perspective view of a control panel showing our new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

The broken lines in the drawings depict portions of the control panel that form no part of the claimed design.

1 Claim, 8 Drawing Sheets
